(57) **CLAIM**

The ornamental design for an arcade video game machine, as shown and described.

DESCRIPTION

FIG. 1 is a front view of an arcade video game machine showing our new design;

FIG. 2 is a rear view thereof;

FIG. 3 is a top plan view thereof;

FIG. 4 is a bottom plan view thereof;

FIG. 5 is a right side view thereof;

FIG. 6 is a left side view thereof;

FIG. 7 is a front view showing an operating condition thereof in which a condition where a sword-shaped controller is moved upward while the game proceeds is shown;

FIG. 8 is a right side view showing an operating condition thereof in which a condition where a sword-shaped controller is moved upward while the game proceeds is shown;

FIG. 9 is an enlarged sectional view taken along the line 9—9 of FIG. 8 from which an inner mechanism is omitted, in which a condition where a sword-shaped controller is moved upward while the game proceeds is shown; and,

FIG. 10 is a front perspective view thereof.
